UNITED STATES PATENT OFFICE

121,007

DESIGN FOR A PUZZLE

John D. Boyle, Greenwich, Conn.

Application March 19, 1940, Serial No. 91,060

Term of patent 3½ years

To all whom it may concern:

Be it known that I, John D. Boyle, a citizen of the United States, residing at Greenwich, county of Fairfield, State of Connecticut, have invented a new, original, and ornamental Design for a puzzle, of which the following is a specification, reference being had to the accompanying drawing, forming part thereof.

Fig. 1 is a face view and

Fig. 2 is a rear view of my new design for a puzzle.

I claim:

The ornamental design for a puzzle, substantially as shown.

JOHN D. BOYLE.
